Alley Carlson

Salem, Oregon.

The undersigned is the author of the patent and making part of the same containing a description in the words of the said Alley Carlson himself of his machine for setting Wells in a conductor.

The machine for receiving and extracting the stone, gravel &c from the well consists of wood or sheet iron resembling a tub or barrel sawed in half, which may be varied in length or diameter, to the convenience of the user said machine being so nearly cylindrical, as for the diameter of the upper end or top, not to exceed the diam' of the lower end more than one half or $\frac{1}{4}$ of an inch, for the purpose of receiving two iron steps, one near the top and the other at the bottom or smallest end to strengthen it, whether it be composed of wood or sheet iron, except the centre of the bottom is freed the cutter which consists of iron and steel, answering to the description of the auger, within or under said cutter crooking at right angles; the centre of said cutter and diameter of the machine is a strip of iron equal in dimensions to that of the cutter which serves as a support to the works, besides which there are several other pieces of a like size; for the purpose of hanging the cutter, having to the works etc. all which bears up on the outside of the machine and are fastened with screws &c. The bottom or lining of the machine with its the above described iron frames in, or may be sheet iron, and requires to be nearly or quite watertight, except the centre of the top extends from inside to inside a piece of wood the centre of which a piece of iron with a socket at the upper end of 16 by 16 inches and running to a point at the lower end passing thro the centre of the iron frame at the bottom answering to the centre or eye of the auger. The socket above mentioned to place the shank or shaft in, two pieces or strips of iron of a like size intended to be placed around except the bottom in a parallel line with the horizontal cutting, one on the one side, and the other on the other side, about 6 in

from the cutter which forms the length of the valves, and so as taking them on, in the outward circumference of the machine is placed two perpendicular cutters or knives, about four inches in length, at proportionate distances from each other which meets, or crosses the margin of the perpendicular cut of the auger and operates independent of the auger. When the machine is working in its operation the centre auger or plumb cuts off the centre of the castle, the perpendicular cut, or knife, cuts off the circumference similar to that of the centre cut, while the horizontal cutter, answering to that of the auger, runs under the earth between the circumference and centre of the machine, and receives it into the mouth of each valve, which valve the construction is, downward, the free part of the valve gradually arises from the cutter in proportion to the thickness of the earth between the valves, and the cutter answering to the core or bores of the auger until the machine is full when raised from the bottom, the valves just close on the top of the horizontal cutter and prevent the sand or bores from returning, by which means the machine being full consequently will hold no water. With respect to the other part of the apparatus described in the draught for the purpose of boring clay &c. it consists of iron particularly the socket and braces, the cutters thereof are steel'd and temper'd; the socket is about 1 in. square at top tapering downward to a point, similar to the other parts of above, both being wrought with the same shaft sinker, 3 in. 6 in. from the lower end of the point . . . . . or plumb, is a hole about $\frac{1}{4}$ in. or more in diameter to which the horizontal cutters are fixed, with a shoulder and lip laying on opposite sides of the plumb, each lip being perforated agreeing with that in the plumb, this which is placed in neck forming a joint; below the socket is a band of iron or traveller up and down, on opposite sides of neck is fastened one end of each brace, the other end extending to the horizontal cutter within 6 or 8 in. of the outward end and fastening to it, so that the machine being strongly by the socket the traveller and outward end of the cutters will by means of the neck joint and

contracts the chain & again when it is let down into the well is compressed to the earth it expands so lengthwise in chain. It appears to scratch the outside of the rock. and when here around with bars of handspikes, as the other part of the machine described above, it cuts and permits excavation no larger or larger and smaller. By introducing a pin line below the rock & and above the boarders, then the diameter of the well the outward end of the cutter are sharpened and turned down being as perpendicular cutter to all the circumference.
